UNITED STATES PATENT OFFICE.

JOHN HERNACKI, OF CHICAGO, ILLINOIS.

ROLLING SCREEN.

1,371,892.

Specification of Letters Patent. Patented Mar. 15, 1921.

Application filed March 13, 1919. Serial No. 282,474.

To all whom it may concern:

Be it known that I, JOHN HERNACKI, a citizen of the United States of America, residing at Chicago, in the county of Cook and State of Illinois, have invented new and useful Improvements in Rolling Screens, of which the following is a specification.

The purpose of the invention is to provide a rolling screen for windows, the screen comprising a spring actuated roller rotatably mounted in a housing adapted for attachment to a window frame at the top, preferably on the outside. The screen is bound upon either longitudinal edge by suitable flexible strips riveted or otherwise suitably attached together on opposite sides of the screen and these strips carry suitable guide hooks movable in guides mounted on the window frame. Means is provided for locking the screen, so that the lower edge thereof may stand at various heights from the sill of the window.

The invention is illustrated and described in a specific embodiment, to which, however, it is not to be restricted. The right is reserved to make such changes or alterations as the actual reduction to practice may suggest, in so far as such alterations or changes are compatible in spirit with the annexed claim.

In the accompanying drawings:

Figure 1 is a view in front elevation showing a window frame with the improved screen attached thereto.

Fig. 2 is a section on the line 2—2 of Fig. 1.

Fig. 3 is a section on the line 3—3 of Fig. 1.

Fig. 4 is a detailed elevational view of the binding strips and hooks for the edge of the screen.

Fig. 5 is a section on the line 5—5 of Fig. 4.

Fig. 6 is a detailed sectional view of the guide tracks for the longitudinal edges of the screen.

In the drawings there is shown a window frame having the sill 1 and the outside architrave on the vertical stiles of which there are attached the guides generally designated 2, these guides serving to hold intact the longitudinal edges of the screen 3.

The screen is of the usual wire mesh and is carried upon the outer steel shell 4 which

constitutes the outer covering for a roller 5, 55 the latter being of less length than the length of the shell to provide a space in the shell adjacent one end which is spanned by a rod 6, the latter connecting a disk member 7 with the roller 5, the disk member 7 60 lying adjacent one end of the shell 4, and carrying a stud 8. The roller 5 at the opposite end of the shell against which it lies carries a pivot stud 9.

The roller is incased within a housing 10 65 appropriately supported at the upper end of the window frame and in one end of this housing the stud 9 is rotatably mounted while in the opposite end the stud 8 is fixed, the roller being mounted for angular movement on the disk 7 which connects with the stud 8. A spiral spring 10 surrounds the rod 6 and has one end fixed in the disk 7 and the other end fixed in the roller 5. It is thus apparent that as a roller is rotated a torsional strain is imposed upon the spring 10 75 so that the spring tends to rotate the roller in the opposite direction immediately the strain is removed.

The screen 3 being attached to the shell 80 4, as the screen is lowered the torsional strain referred to is imposed upon the spring 10, and when the force tending to lower the screen is removed the spring acts to rotate the roller in such a direction as to coil the 85 screen 3 thereon.

The guides 2 are formed preferably each of a single piece of flat metal bent back on itself to provide a flange portion 11, one section of the stock being shaped to provide a 90 channel for track portion 12 lying adjacent the flange portion 11. The two remaining portions 13 and 14 and the stock forming the guide are spaced apart, as clearly shown in Fig. 6, and the two legs or flanges thus 95 provided are crimped as shown at 15 and 16 to provide two longitudinal inset ribs.

The screen in being raised or lowered moves between the flanges or legs 13 and 14 and the longitudinal edges of the screen are 100 each equipped with binding strips 17 placed on opposite sides of the screen and appropriately secured together by suitable fastening means, these strips serving to secure at suitably spaced intervals the L-shaped members 18, the free legs of which move in the 105 channel or guide portions 12.

The flange or leg 13 of each guide 2 is

made wider than its mate 14, and this wider flange is positioned behind the screen 3 as viewed from the outside of the window and is formed on its edge with notches 19 provided for engagement with a suitable latching mechanism carried on the inner face of the transversely disposed bar 20, the latter being carried at the lower or free end of the screen 3, and serving as a reinforcing member for the lower edge.

The latching mechanism for the screen comprises two horizontal rods 21 mounted in suitable slide bearings 22 carried upon the inner face of the bar 20. These rods 21 terminate in thumb engaging portions 23, which are positioned adjacent each other so that the remaining ends of the rods which are appropriately flattened may engage the notches 19 formed in the flanges 13 of the guides 2. Compression springs 24 surrounding the rods tend to force them normally in the direction for engagement with the notches 19 and the rod may be relieved from such engagement only on the application of the pressure on opposite sides of the thumb or finger engaging members 23. So long as the rods 21 engage the notches 19, the screen 3 is held in any position of closure to which it may be adjusted. Obviously on the release of the rods from the notches, such as would be the case when the thumb engaging portions 23 are pressed toward each other, the screen 3 may be raised or

lowered as a result of being carried by the spring actuated roller hereinbefore referred to.

From the foregoing description and the accompanying drawings, it is believed that a clear enough understanding of the invention is to be had to render further description unnecessary.

The invention having been described, what is claimed as new and useful is:

In a device of the kind described, a spring actuated roller, a screen carried by the roller, guides for the side or longitudinal edges of the screen, the said guides being formed of a single piece of flat metal bent back on itself to provide an attaching flange portion, one section of the stock of the guide being shaped to provide a channel adjacent the said attaching flange portion and a guide flange connected with said stock and at right angles to the same, the remaining portion of the stock of the guide being formed to provide a guide flange paralleling the first said flange both flanges being crimped to provide inset ribs between each of the edges of the screen slides, and L shaped members attached to the side edges of the screen at spaced intervals and having their free legs slidingly engaging the channel portions of the guides and their remaining legs moving between the guide flanges.

In testimony whereof I affix my signature.
JOHN HERNACKI.
